OF SYRACUSE, NEW YORK, A CORPORATION OF NEW YORK.

CASING FOR INCANDESCENT-ELECTRIC-LAMP SOCKETS.

1,075,539.

Specification of Letters Patent.

Patented Oct. 14, 1913.

Application filed February 18, 1911. Serial No. 609,350.

To all whom it may concern:

Be it known that I, CARL H. BISSELL, of Syracuse, in the county of Onondaga and State of New York, have invented a certain 5 new and useful Casing for Incandescent-Electric-Lamp Sockets, of which the following is a specification.

This invention has for its object the production of a casing for incandescent electric lamp sockets, which can be readily applied to, and removed from, the socket; and it consists in the combinations and constructions hereinafter set forth and claimed.

In describing this invention reference is had to the accompanying drawing in which like characters designate corresponding parts in all the views.

Figure 1 is an unassembled view of the members of the casing, the cap member being shown in section and the lower portion of the shell member being broken away. Fig. 2 is a fragmentary sectional view illustrating the position of the cap and shell members prior to the interlocking of the shoulders thereof. Fig. 3 is a view similar to Fig. 2 illustrating the position of the parts when such shoulders are interlocked. Fig. 4 is a section on line "A—A" Fig. 3. Fig. 5 is an end view of the cap member looking upwardly. Fig. 6 is an end view of the shell member looking downwardly. Fig. 7 is a detail view of the ring associated with the cap member.

This casing for incandescent electric lamp sockets comprises a shell member and a cap member, one being formed with an internal annular groove and having shoulders associated therewith and projected inwardly into the groove, and the other member being formed with peripheral shoulders near one end thereof for interlocking with the first-mentioned shoulders, the cap and shell members having successive axial and partial rotative movements relatively to each other 45 for interlocking said shoulders.

In this embodiment of my invention the cap member is formed with a groove and internal shoulders and the shell member with peripheral shoulders.

50 1 is the cap member and 2 is the shell member, the cap member being formed with an intermediate cylindrical portion 3 and an offset annular portion 4 forming an internal annular groove 5 below the cylindrical portion 3. The cap member is also formed

55

with inwardly facing notches 6 at its lower end. Usually a ring 7 is fitted within the groove 5, such ring having a series of inwardly projecting shoulders 8 pressed therefrom. These shoulders are usually formed 60 by slitting the ring horizontally once for each shoulder and pressing inwardly the portions of the ring below the slits. The cap member is also formed with a suitable coupling 9 by means of which the casing is 65 secured to the supporting fixture.

The shell member 2 is formed with downwardly facing shoulders 10 near its upper end, the upper end portion 11 of the shell member being designed to fit into the intermediate cylindrical portion 3 of the cap member (Fig. 3) by an axial movement of the members 1, 2, the shoulders 10 during such axial movement passing between shoulders 8 of the ring 7 and being moved 70 into interlocking engagement therewith by partial rotation of the shell member. The shell member 2 is also formed with a spring catch 12 in the form of a tongue struck from the shell member, said catch being 75 designed to snap into one of the notches 6 when the shoulders 10 interlock with the shoulders 8. The shoulders 10 are formed in the shell member in the same manner as the shoulders 8 are formed in the ring 7.

80

If for any reason it is necessary to remove the socket from the casing, the shell member 2 can be quickly removed by depressing the catch 12 out of the notch 6 with which it is engaged, by turning the shell member until the shoulders 10 thereof are aligned with the spaces between the contiguous shoulders 8 and then withdrawing the shell endwise.

85

What I claim is:

90

1. A casing for incandescent electric lamp sockets comprising a shell member having a peripheral projection, and a resilient locking member and a cap member having an internal shoulder for co-operating with said projection, and a notched edge for permitting the passage of the projection and for co-operating with the locking member, substantially as and for the purpose described.

95

2. A casing for incandescent electric lamp 100 sockets comprising a shell member and a cap member, one being formed with an internal annular groove and provided with a ring in the groove formed with inwardly projecting shoulders struck therefrom, the end por-

105

110

- tion of the other member extending into the first-named member and having substantially rigid peripheral shoulders for interlocking with the shoulders of the ring, and 5 the members having successive axial and partial rotary movements for interlocking said shoulders, substantially as and for the purpose specified.
3. A casing for incandescent electric lamp 10 sockets comprising a cap having an annular portion for receiving the end portion of the shell member, and an edge for coöperating with said shell member, and an offset annular portion intermediate the first-named 15 annular portion and said edge, said offset annular part having inwardly extending projections, and a shell member having a plain marginal edge portion for entering the first-named annular portion, and having 20 a peripheral projection coacting with said projections and having a yielding tongue co-operating with the edge portion of the cap, substantially as and for the purpose specified.
- 25 4. A casing for incandescent electric lamp sockets comprising a shell member and a cap member, the cap member being formed with an internal cylindrical portion and an offset portion between said cylindrical portion and 30 the lower end of the cap, the offset portion forming an annular groove, a ring fitted within the groove and formed with shoulders struck therefrom projecting into the groove and spaced apart at intervals, the 35 shell member being provided with substantially rigid peripheral shoulders spaced apart for interlocking with the first-mentioned shoulders, the upper end portion of the shell member being designed to fit into 40 the cylindrical portion of the cap member, and the members having successive axial and partial rotary movements for moving the upper end portion of the shell member into 45 said cylindrical portion of the cap member, and carrying the shoulders of the shell member between the shoulders of said ring and into interlocking engagement therewith, substantially as and for the purpose described.
- 50 5. A casing for incandescent electric lamp sockets, comprising a shell member and a cap member, the cap member being formed

with an intermediate cylindrical portion and an off-set portion between the cylindrical portion and the lower end of the cap, the 55 off-set portion forming an annular groove, shoulders associated with the cap member and projecting into the groove, the shoulders being spaced apart, the shell member being provided with substantially rigid peripheral 60 shoulders for interlocking with the shoulders of the cap member, the upper end portion of the shell being designed to fit into the cylindrical portion of the cap member, and the members having successive axial 65 and partial rotary movements for moving the upper end portion into the cylindrical portion of the cap member and carrying the shoulders of the shell member above the shoulders of the cap member and into interlocking 70 engagements therewith, the cap member being provided with internal notches at its lower end and the shell portion being provided with a catch for entering into a notch, said catch being in the 75 form of a spring tongue, substantially as and for the purpose specified.

6. A casing for incandescent electric lamp 80 sockets comprising a shell member and a cap member, the cap member being provided with an internal ring of sheet metal formed with a plurality of inwardly projecting shoulders spaced apart, and the shell member being formed with external projecting shoulders, the shoulders of the shell and cap 85 being movable into interlocking engagement by successive axial and partial rotary movements of said members, and each shoulder being formed by forming the part provided therewith with a slit extending circumferentially thereof and displacing the metal adjacent said slit to project from said part, substantially as and for the purpose 90 set forth.

In testimony whereof, I have hereunto 95 signed my name in the presence of two attesting witnesses, at Syracuse, in the county of Onondaga, in the State of New York, this 13th day of January, 1911.

CARL H. BISSELL.
